UNITED STATES PATENT OFFICE

CHARLES F. SILVEUS, OF WAYNESBURG, PENNSYLVANIA

FRUIT-JUICE EXTRACTOR

Application filed May 22, 1928. Serial No. 279,700.

The invention relates to devices for extracting the juice from oranges and analogous fruit, with only the necessity of forming a single opening through the skin, and it is one object of the invention to provide a new and improved device which is provided with a drinking spout through which the juice may be discharged directly into the mouth.

A further object is to provide a device of the class set forth provided with unique means whereby such a seal is provided as to prevent leakage of juice.

A still further object is to provide novel means whereby the same device acts first as a web cutter and core remover, and thereafter acts to receive the juice to discharge it either into the mouth or into a receptacle.

With the foregoing in view, the invention resides in the novel subject matter herein-after described and claimed, description being accomplished by reference to the accompanying drawing.

Fig. 1 is a side elevation looking in one direction and showing the relation of the device 25 with an orange, by dotting the latter.

Fig. 2 is a side elevation at right angles to Fig. 1.

Fig. 3 is a vertical sectional view on line 3—3 of Fig. 1.

Fig. 4 is a horizontal section on line 4—4 of Fig. 2.

The drawing above briefly described, illustrates the preferred form of construction, and while this construction will be herein specifically explained, it is to be understood that within the scope of the invention as claimed, variations may be made.

The numeral 5 denotes an elongated rigid tube either constructed entirely of material which will not be affected by fruit juice, or coated with such material. One end of this tube is provided with a channel-shaped drinking or pouring spout 6, and at the inner end of said spout, is surrounded by an outstanding flange 7 of such transverse shape as to allow it to tightly abut the skin 8 of an orange or the like. Adjacent the flange 7, the body is provided with an outstanding helically disposed web 9 having a sharp end 10. When an opening is formed through the skin 8 in a

manner hereinafter described or by other suitable means if desired, the tube 5 is forced into this opening and when the web end 10 comes in contact with the skin, turning of the tube 5 in the proper direction causes said web to 55 thread through the skin, thus so tightly clamping the latter against the flange 7, as to prevent any juice leakage between tube and skin. To assist in turning the tube, the longitudinal edges of the spout 6 are provided 60 with outwardly projecting wings 11 which are integral with said edges and are also integrally joined to the flange 7. In addition to forming finger grips, these wings relatively brace the spout 6 and the flange 7 and they 65 also constitute guards to prevent the edges of the spout from cutting the upper lip, when the spout 6 is inserted into the user's mouth, permitting him to drink the orange juice which is received in the tube.

The inner end of the tube 5 is open to permit passage of juice into said tube from the orange, and said tube is provided with a number of openings 12 which also serve to conduct the juice to the interior of the tube. 70 Said inner end of the tube 5 is provided with a number of helically directed splits 13, leaving similarly directed fingers 14 between the splits. These fingers are longitudinally tapered toward their free ends and a portion 75 of each finger between its center and its butt end, is provided with a sharp cutting edge 15. Then too, a sharp-edged cutting tooth 16 is provided substantially at said center. Each finger is longitudinally curved so that 80 its free, sharp end 17 extends partially across the lower end of the tube 5, as seen most clearly in Figs. 3 and 4.

Turning of the tube in a clockwise direction after placing the teeth 16 against the skin 90 of an orange, causes these teeth and the edges 15 to cut a circular disk from the skin. Then, continued rotation of the tube and inward pressure thereon, causes it to cut the entire core of the orange loose from the surrounding juice cells, the webs of the segments, being also cut by this operation. By the time the web 10 has about reached the skin, the core of the orange has been literally 95 twisted from the underlying portion of the 100

orange, and by now rotating the tube in the opposite direction, the prongs 17 impale the core so that upon withdrawal of the tube, said core will also be withdrawn. At this point, 5 attention may be directed to the longitudinal taper of the tube 5. This taper insures that the core shall not frictionally contact with the inner side of the tube so tenaciously as to prevent easy removal of said core after with- 10 drawing the tube from the orange. By tapping the spout 6 upon a table or other object with the spout end of the tube disposed downwardly, this core may be readily removed. The entire tube may now be reinserted 15 through the opening in the skin and rotated to cause the web 10 to thread through said skin, tightly clamping it against the flange 7. This action and the taper of the tube, thus form a juice-tight connection between 20 tube and skin, so that there is no danger of leakage around the device. By now pressing upon the orange, the juice cells are broken and the freed juice enters the tube 5, from which it may be poured through the spout 25 6, either into a receptacle or into the user's mouth. If the spout be inserted into the mouth, the flange 7 prevents the lips from touching the orange peel and the wings 11 prevent the longitudinal edges of the spout 30 from possibly cutting the upper lip.

The device is exceptionally simple and inexpensive, yet is efficient and very desirable. On account of such advantages, the details disclosed are preferably followed. However, 35 within the scope of the invention as claimed, variations may be made.

I claim:

1. A device of the class described comprising a juice discharge tube for insertion 40 into an orange through an opening in the skin thereof, a flange on said tube to abut the orange skin, and means at the exterior of said tube adjacent said flange to pass through the skin and hold said flange in juice-tight contact with said skin.

2. A device of the class described comprising a juice discharge tube for insertion into 45 an orange through an opening in the skin thereof, a flange on said tube to abut the orange skin, and a helically disposed web on the exterior of said tube adjacent said flange, said web being adapted to thread through the skin and hold said flange in juice-tight contact with said skin.

55 3. A device of the class described comprising a juice discharge tube for insertion into an orange through an opening in the skin thereof, the outer end of said tube having a channel-shaped drinking spout, an outstand- 60 ing flange on said tube at the inner end of said spout adapted to abut the orange skin, a helically disposed web on said tube adjacent said flange adapted to thread through the skin and hold said flange in juice-tight contact with said skin, and wings projecting

laterally from the longitudinal edges of said spout to prevent cutting of the upper lip therewith and to act as finger pieces for turning the tube to thread said web through the orange skin.

70

4. An article of manufacture for successively coring and receiving juice from an orange, comprising a tube having means for entirely dislodging the core from an orange and for holding the dislodged core in the 75 tube while the latter is being removed, and juice-stopping means on said tube to abut the orange skin upon reinsertion of the tube after core removal.

5. A structure as specified in claim 4; together with means on said tube below said juice-stopping means to pass through the orange skin and hold said juice-stopping means in juice-tight contact with said skin.

6. An article of manufacture for successively coring and receiving juice from an orange, comprising a perforated coring and juice-receiving tube having sharp-edged cutting means at one end operative upon turning of the tube in one direction, and inwardly projecting sharp-ended core-impaling prongs operative upon turning of said tube in the other direction.

7. An article of manufacture for successively coring and receiving juice from an orange, comprising a perforated coring and juice-receiving tube having sharp-edged cutters at one end operative upon turning of the tube in one direction, and spirally-directed core-impaling prongs projecting inwardly 100 from said cutters and operative upon turning of the tube in the other direction.

8. A structure as specified in claim 7; together with outwardly projecting cutting teeth at the juncture of said cutters and 105 prongs.

9. An article of manufacture for successively coring and receiving juice from an orange, comprising a coring and juice-receiving tube provided at its lower end with core-dislodging means operable upon turning of the tube, the upper end of said tube being provided with a channel-shaped drinking spout, and wings projecting laterally from the longitudinal edges of said spout to prevent cutting of the upper lip therewith and to act as finger pieces for turning the tube during the core-dislodging operation.

In testimony whereof I have hereunto affixed my signature.

CHARLES F. SILVEUS.
